UNITED STATES PATENT OFFICE.

ANDREW J. PARLIN, OF NEWPORT, KENTUCKY.

DESIGN FOR AN EASEL.

SPECIFICATION forming part of Design No. 22,244, dated February 29, 1893.

Application filed January 9, 1893. Serial No. 457,840. Term of patent 3½ years.

To all whom it may concern:

Be it known that I, ANDREW J. PARLIN, a citizen of the United States, and a resident of Newport, in the county of Campbell and State of Kentucky, have invented a certain new and Improved Design for Easels, of which the following is a specification.

My invention is a new and original design for easels.

10 The distinctive features of my design are the frame, rear support and the side racks formed to represent twisted strand or rope, as fully illustrated in the accompanying drawings, in which:

15 Figure 1 is a perspective view of an easel made according to my design, and Fig. 2 is an edge elevation of the same.

The lower rail A, having downwardly extending loops a, forming legs or feet upon which the frame of the easel rests, and the vertical upright pieces A', are formed of a single piece of twisted material. The inner uprights B are, at the bottom, looped around the lower rail A, extend up vertically and are bent at, substantially, a right angle to form the top a', the horizontal portion being carried across to meet the outside upright A', and the ends of the two parts are twisted together to form the loops or bows a''. C is a 20 twisted rail extending between the vertical uprights B, bent down at each end and looped over the lower rail A. The rail is also apparently secured to the vertical uprights B by single strands or loops c. The upper cross rail D, which is also formed of twisted mate-

rial, extends across from one upright A' to the other and is looped around each at d. The rear supporting brace or leg is formed of two twisted rods E, the lower ends of which are lapped around to form feet e. The rails 40 E are twisted together at e' and diverge from that point to the feet e, and to the upper ends e''. These upper ends are intertwined with the easel cross brace D, and the lower divergent parts of the legs are braced by a transverse twisted rod e', which is twisted around each of the divergent legs of the brace. The shelves F are each formed of a single piece of twisted material, bent downwardly at each end at a right angle and thence bent backwardly at a substantial right angle and twisted around the vertical uprights A' and B. There are shown eight of these upon each side, forming a rack to hold such articles as may be desired. Similar shelves F' 50 depend from the transverse bar C, the vertical upright ends being twisted around said bar, carried down and then bent up to form shelves or brackets to either support the frame of a picture when framed, or to contain appropriate articles when an unframed picture is held in the easel.

What I claim as new, and desire to secure by Letters Patent, is--

The design for an easel, substantially as 65 herein shown and described.

ANDREW J. PARLIN.
